INTERMEDIATE PRESSURE TAKE-OFF FROM BARREL TYPE BOILER FEED PUMPS

Milton W. Lutz, Wauwatosa, Wis., assignor to Allis-Chalmers Manufacturing Company, Milwaukee, Wis.

Application December 9, 1957, Serial No. 701,413

3 Claims. (Cl. 103—108)

This invention relates to double casing multiple stage pumping units. More specifically this invention relates to improvements in double casing multiple stage centrifugal pumps to provide a means to withdraw fluid at intermediate pressure from an intermediate stage in the pump.

A double casing multiple stage centrifugal pump is often used as a boiler feed pump in power houses. It is desirable in power houses to have available fluid at a pressure other than the high terminal pressure obtained from double casing multiple stage pumps. In the past, this has been done by providing an auxiliary pump to generate the desired pressure, or by tapping through the double casing to the pump stage generating the desired pressure. A leakage problem was encountered when tapping fluid from an intermediate stage of a multiple stage pump because the relative movement between the inner and outer casing made it difficult to adequately seal the conduit carrying the fluid at intermediate pressure where it passes through the outer casing.

The relative movement between the inner and outer casing is due to the outer casing being subjected to high discharge pressure to its inner side and to atmospheric pressure to its outer side. Therefore, while the pump is operating, the outer casing distorts in an outward direction. On the other hand, the inner casing is subjected to the high discharge pressure of the pump on its outer side, and on its inner side, is subjected to pressures that vary at each pumping stage, but certainly much above atmospheric pressure. Because of the design and the inherent high compression strength of the casing material, the inner casing has relatively good resistance to deformation as compared to the outer casing. The pressure differential on the inner casing is much less than on the outer casing. The pressure differential that does exist results in a squeezing effect, and because the casing material has high compression strength, the inner casing will remain relatively stationary while the pump is operating. The result of all the forces acting on the casings is to cause the outer casing to expand and to move outward relative to the inner casing while the pump is operating.

In the pump of this invention, an annular member hereinafter called a stuffing box, surrounds the shaft and is attached to the inner casing. The stuffing box, therefore, is stationary relative to the inner casing. The outer casing is slidably mounted on the stuffing box to allow movement relative to the inner casing. The stuffing box is provided with a passageway extending therethrough that connects the area between the inner and outer casings to the atmosphere. A port is provided in the volute of any pumping stage to withdraw fluid at an intermediate pressure. A conduit extends in the area between the inner and outer casing and connects the port to the inboard end of the passageway in the stuffing box. Means are provided at the outboard end of the passageway in the stuffing box for receiving and distributing the fluid from the intermediate pressure stage. Hence the intermediate pressure conduit extends from one member through a relatively stationary member rather than

2

through a relatively movable member as was done in the prior art.

An object of this invention is to provide new and improved means for obtaining fluid from any stage of a double casing multiple stage centrifugal machine.

Another object of this invention is to provide a new and improved leakless intermediate fluid take-off in double casing multiple stage centrifugal machines.

Another object of this invention is to provide a new and improved intermediate fluid take-off in double casing multiple stage centrifugal machines that is easy to assemble.

Objects and advantages other than those above set forth will be apparent as the description of the invention proceeds.

The novel features of the invention and how the objects are obtained will appear from the following description and the accompanying drawings showing an embodiment of the invention and forming a part of this application and all these novel features are intended to be pointed out in the claims.

In the drawings:

Fig. 1 is a longitudinal section of a portion of a double casing multiple stage centrifugal pump embodying the invention;

Fig. 2 is a cross section of Fig. 1 taken at line II—II; and

Fig. 3 is a cross section of Fig. 1 taken at line III—III.

The pump as shown in Fig. 1 is of usual double casing design similar to the pump described in U.S. Patent 2,668,502, E. J. Blackwell, issued February 9, 1954. The double casing multiple stage centrifugal pump embodying the invention comprises an outer casing 1, an outer casing cover 2, an inner casing 3, a series of pumping stages such as 4, 5, 6, 7, 20 and a stuffing box 8.

The outer casing 1 is opened at one end 12 and has an inlet (not shown) and outlet 9. A casing cover 2 defining a centrally located aperture 11 is removably attached to the open end 12 of outer casing 1.

The inner casing 3 is mounted in the outer casing 1. The inner casing 3 has an inlet (not shown) and an outlet 13 which are aligned with and communicate respectively with the inlet (not shown) and outlet 9 of the outer casing 1. As shown in Fig. 1, the inner casing 3 is also provided with a series of annular passageways or volutes, such as 13, 16, 17, 18, and 19 that form pump stages 4, 5, 6, 7, and 20. All the stages of the pump are hydraulically connected in a successive series, for example, the discharge 55 of stage 5 enters the inlet 66 of stage 6 and so on to the next successive stage until the terminal stage 20 is reached.

A shaft 14 is rotatably mounted in the inner casing 3 and extends through the aperture 11 in the cover 2. Impellers 15 are mounted on the shaft 14 for rotation therewith and are operatively disposed to rotate within the volutes such as 13, 16, 17, 18, 19 of the inner casing 3. The impellers 15 transmit the fluid from the inlet of the first stage (not shown) at inlet pressure through the axially spaced and hydraulically connected stages to the terminal stage 20, successively increasing the pressure in each stage.

Suitable means are provided to support the inner casing 3 in proper axial alignment relative to the outer casing 1. In the preferred embodiment of this invention, as shown in Fig. 1, a stuffing box 8 surrounds the shaft 14 to seal the shaft 14 to the inner casing 3 and to maintain the inner casing 3 in proper axial alignment with the outer casing 1. The stuffing box 8 is attached to the inner casing 3 by suitable means such as by bolts 28 and is positioned in the aperture 11 of the cover 2. The cover 2 is slidably mounted on the stuffing box 8 and packing means 29 are positioned between the stuffing

box 8 and the cover 2 to insure a liquid tight seal. This arrangement allows axial expansion of the outer casing 1 relative to inner casing 3 in response to the changes in pressure and/or temperatures within the outer casing 1.

To obtain fluid at intermediate pressure, a port 21 is provided in the discharge volute of an intermediate pumping stage such as the volute 55 of stage 5. This port 21 is provided with means to receive conduit 22. A passageway 23 is defined in stuffing box 8 and connects the area intermediate the casings to the atmosphere. The inboard end 24 of passageway 23 is provided with means to receive the conduit 22. The conduit 22 connects the port 21 to the inboard end 24 of passageway 23. The conduit 22 may be provided with coupling means 26 intermediate its ends for ease in assembling or to allow fluid to be withdrawn from other pumping stages. The conduit 22 connecting the port 21 and the inboard end 24 of the passageway 23 extends in the area between the inner and outer casings as shown in Fig. 2.

A discharge conduit 27 is connected to the outboard end 25 of the passageway 23 in the stuffing box 8, and suitable external means are provided for receiving and distributing the withdrawn fluid.

In operation, fluid at desired pressure, passes from the discharge volute 55 through the port 21 into the conduit 22 hence into the passageway 23 of stuffing box 8. It passes through the passageway 23, being received by the discharge conduit 27 having means to receive and distribute the fluid withdrawn.

The volume of fluid withdrawn from the intermediate stage will be limited by the respective sizes of the port, the conduit and the passageway.

It is understood that the foregoing illustrative description is intended to definitely exemplify applicant's invention and is in no way intended to limit the scope thereof other than as may be reflected in the terms of the claims appended hereto.

What is claimed is:

1. A double casing multiple stage centrifugal machine comprising: an outer casing having an inlet and outlet; an inner casing disposed within and spaced from said outer casing, said inner casing having an inlet and outlet communicating respectively with said outer casing inlet and outlet; a series of axially spaced and connected volutes within said inner casing to transport fluid from said inlet to said outlet; a shaft rotatably disposed within said inner casing, said shaft extending axially through one end of said outer casing; impellers mounted on said shaft for rotation therewith and positionable in said volutes to propel the fluid from said inlet to said outlet; a stuffing box surrounding said shaft and attached to said inner casing, said outer casing slidably mounted on said stuffing box, and packing means to seal said shaft and said outer casing to said stuffing box; and means to withdraw fluid from an intermediate said volute, said means comprising said intermediate volute having a port defined therein connecting said intermediate volute to the area intermediate said casings, a passageway defined in said stuffing box connecting the area intermediate said casings to the atmosphere, a conduit extending in the area intermediate said casings and connecting said port to the inboard end of said passageway and a discharge conduit connected to the outboard end of said passageway to receive and distribute the withdrawn fluid.

2. A double casing multiple stage centrifugal pump comprising: an outer casing having an inlet and outlet for the flow of fluid therethrough; an inner casing within

and spaced from said outer casing, said inner casing having an inlet and outlet communicating respectively with said outer casing inlet and outlet; pumping means within said inner casing, said pumping means including a predetermined number of hydraulically connected volutes to transport the fluid from said inlet to said outlet; a shaft rotatably disposed within said inner casing, said shaft extending axially through one end of said outer casing; impellers mounted on said shaft for rotation therewith and positionable within said volutes to transmit the fluid from said inlet to said outlet; a stuffing box surrounding said shaft and attached to said inner casing, said stuffing box positioned within one end of said outer casing to align said inner and outer casings, said outer casing being slidably mounted on said stuffing box; packing means to seal said shaft to said stuffing box and said outer casing to said stuffing box; and means to withdraw fluid at an intermediate pressure from said pump, said means comprising a port located in an intermediate said volute, a passageway extending through said stuffing box connecting the area intermediate said casings to the atmosphere, a conduit extending in the area between said inner and outer casings connecting said port to the inboard end of said passageway, and means connected to the outboard end of said passageway for receiving and distributing said withdrawn fluid.

3. A double casing multiple stage centrifugal pump comprising: an outer casing open at one end and having an inlet and an outlet; a cover suitably mounted on said outer casing and defining a centrally located aperture; an inner casing mounted within and spaced from said outer casing, said inner casing having an inlet and an outlet communicating respectively with said inlet and outlet of said outer casing and a plurality of axially spaced volutes hydraulically connected in series to form pump stages; a shaft rotatably mounted within said inner casing, said shaft extending axially through said aperture in said cover; a series of axially spaced impellers mounted on said shaft for rotation therewith and positionable within said volutes to transmit the fluid from said inlet to said outlet; a stuffing box attached to said inner casing, said stuffing box being positioned within said aperture in said cover and surrounding said shaft; packing means to seal said shaft and said cover to said stuffing box; and means to obtain fluid from an intermediate pumping stage, said means comprising a passageway defined in said stuffing box connecting the area intermediate said casings to the atmosphere, a said volute of an intermediate pumping stage having a port defined therein connecting said intermediate volute to the area intermediate said casings, a conduit extending in the area intermediate said casings and connecting said port to the inboard end of said passageway, said conduit having coupling means intermediate its ends for assembly, and a discharge conduit connected to the outboard end of said passageway for receiving and distributing said withdrawn fluid.
